UNITED STATES PATENT OFFICE.

PIERRE ZUCCO, OF BALTIMORE, MARYLAND.

ARMORED CEMENT.

No. 821,569.

Specification of Letters Patent.

Patented May 22, 1906.

Application filed June 23, 1905. Serial No. 267,473.

To all whom it may concern:

Be it known that I, PIERRE ZUCCO, a resident of Baltimore, in the State of Maryland, have invented certain new and useful Improvements in Armored Cement, of which the following is a specification.

This invention relates to armored cement or concrete, and more particularly to the construction of the same in the erection of buildings, bridges, pavements, &c.

The object of my invention is to provide an exceedingly cheap and simple system of construction in which the predetermined or estimated size of the pillar or beam, &c., as the case may be, for the required strength is supposedly divided into elements or units which are armored through their respective centers with a small bar of iron or steel of any desirable shape and in such lengths that the connecting of the various bars adapted to form a continuous perpendicular rod will be staggered with respect to the connections of the bars forming the other rods in the pillar or beam, &c., the rods or tension-rods being surrounded and supported at predetermined distances by binders, as in the case of a pillar, or stirrups, as in the case of beams, the construction of the binder and stirrups being substantially the same in each case and each consisting of a small bar bent to form a rectangle within a rectangle, it of course being understood that the entire construction is embodied in the cemented or concreted mass.

With these objects in view and such others as may hereinafter appear my invention consists in the particular construction of the various parts and in the novel manner of combination and arrangement of said parts, all of which will be more fully described, and specifically pointed out in the appending claims.

In the drawings forming a part of this specification, Figure 1 is a sectional view illustrating a portion of a structure comprising a pillar, a beam, and the floor. Fig. 2 is a horizontal sectional view of the pillar. Fig. 3 is a side elevation of the pillar. Fig. 4 is a perspective view of the binder or stirrup, and Fig. 5 is a sectional view of a slab such as is used in the construction of a floor or pavement.

Referring by numerals to the drawings, 1 represents the pillar, 2 the beam, and 3 the flooring, the main portion of each being constructed of cement or concrete armored in accordance with my invention. The pillar 1 is armored with a series of perpendicular rods

4, placed at an equal distance apart, the number varying according to the estimated or calculated strength. In the calculation of the desired strength I divide the pillar into 60 elements or units and so place the rods that they will be in the centers of the respective elements. Each rod consists of a number of short rods secured together or connected at their respective ends by crockets, as shown 65 at 5, such connections being staggered with respect to the connections of the other rods in the series.

The same construction is to be found in the beams 2, except that the tension-rods 6 are in a horizontal position. In both the pillars and the beams I employ a special design of a binder or when used in connection with a beam perhaps better known as a "stirrup." This binder or stirrup 7 consists of a rod bent 75 to form a rectangle within a rectangle, as clearly shown in Fig. 4, the arrangement being such that it will wind four times in the body of the pillar or beam inclosing the perpendicular or tension rods. These binders or stirrups are placed apart at a distance according to the requirements of the estimated strength of the pillar or beam and are alternatively crossed, as clearly shown in Fig. 1.

In the construction of the flooring, ceiling, or pavement I employ a prepared slab 8, having flanges 9 and armored by a series of rods 10, varying in number according to the size. The rods 10 have arms 11, which project beyond the slabs and are adapted to engage the tension-rods 12. These slabs, together with the tension-rods supporting the same, are embodied in cement or concrete, as clearly shown in Fig. 1.

In some cases it may be found desirable to 95 form a flooring with tension-rods placed at equal distances apart, and when so formed I estimate the strength by units or elements and place the tension-rods so that they will be in the center of each element.

Having thus described the various features of my invention, what I claim to be new, and desire to secure by Letters Patent, is—

1. In an invention of the class described, a series of rods formed by a number of short bars, crockets connecting the bars, the connections being staggered, binders or stirrups at an equal distance apart throughout the length of the rods, the said binders or stirrups consisting of a bar bent to form a rectangle within a rectangle, substantially as specified.

2. In an invention of the class described, a series of rods formed by a number of short bars, crocket connections between the bars, the connections being staggered, a series of binders or stirrups arranged alternately with respect to their free ends at regular intervals apart throughout the length of the rods, the said binders or stirrups consisting of a bar bent to form a rectangle within a rectangle, and cement or concrete incasing the entire structure, substantially as specified.

3. In an invention of the class described, a pillar consisting of a series of rods formed by a number of short bars connected by crockets, the connections in the rods being staggered, binders arranged at intervals throughout the length of the pillar, the binder con-

sisting of a rod bent to form a rectangle within a rectangle, cement incasing the structure, a beam comprising a series of tension-rods 20 formed of short bars, crocket connections between the bars, the connections being staggered, stirrups inclosing and supporting the tension-bars, and said stirrups consisting of a bar bent to form a rectangle within a rectangle, cement incasing the whole, a flooring consisting of a series of prepared armored slabs, a series of tension-bars supporting the slabs, and cement incasing the whole, substantially as specified.

PIERRE ZUCCO.
